COMBINATION MACHINE FOR TREATING
RAMIE, FLAX, AND HEMP

Karl Wessel, deceased, late of Los Angeles, Calif.,
by Leland O. Walker, administrator, Los Angeles, Calif., assignor of one-fourth to Charles S. Kirkpatrick, Bloomington, Ill., and three-fourths to American Fiber Corporation, a corporation of Nevada

Application August 5, 1939, Serial No. 288,642

8 Claims. (CL 19—5)

This present invention relates to machines for the treatment of fiber bearing straw or stocks and is in the nature of an extension or further development of the machine disclosed and claimed in a companion application filed of even date herewith S. N. 288,644.

The present machine, like that of said co-pending application, is capable of treating various different kinds of fiber such as ramie, flax and hemp but includes additional mechanism which especially adapts the machine for treatment of ramie. The straw or stock of ramie has a gummy shell that should be broken up before drying and which should be further broken after drying.

The present machine involves a pre-decorticator including primary breaking rollers. The machine further includes a drying mechanism that receives the pre-decorticated fiber and deliver the same on to final decorticator including breaking rollers. The machine involves additional cooperating devices such as carding, picking, scutching and like devices, all of which will be hereinafter described in connection with the drawings wherein like characters indicate like parts throughout the several views.

Because of the extreme length of the complete machine it has been necessary to make the patent drawings thereof in section. These sections are arbitrary and made of such length that each section will properly go on a sheet of patent drawings.

Referring to the drawings:

Fig. 1 is a side elevation showing the first section of the machine;

Fig. 2 is a vertical longitudinal section of the parts shown in Fig. 1;

Fig. 1a is a side elevation showing the second section or part of the machine;

Fig. 2a is a vertical longitudinal section of the parts shown in Fig. 1a;

Fig. 1b is a side elevation showing the third section or part of the machine;

Fig. 2b is a vertical longitudinal section of the parts shown in Fig. 1b;

Fig. 1c is a side elevation showing the fourth or final part of the complete machine; and

Fig. 2c is a vertical longitudinal section of most of the parts shown in Fig. 1c with some of the final elements in full elevation.

The frame work of the machine may be of any suitable form but as shown involves frame members 10, 10a, 10b, 10c, 10d and 10e. The fiber stock, assumed to be ramie, is shown as fed by an endless belt 11 that runs over rollers

12 mounted on the frame section 10. This stock, as shown, is delivered under a presser roller 13 mounted on and yieldingly pressed downward by a supporting spring arm 14 anchored to a suitable part of the frame 10. The stock is thus delivered to a multiplicity of corrugated primary breaking rollers 15 and 16 that are journaled on the frame section 10 and are driven in the direction of the arrows marked on Fig. 2 so that the fiber stock will be delivered between the breaking rollers 15 and 16 and the fiber thereof initially broken up and some thereof removed and dropped from the fiber.

The upper rollers 16 are preferably journaled in bearings downwardly spring pressed by means such, for example, as that illustrated in the prior Wessel Patent No. 1,592,317.

These rollers 15 and 16 constitute the pre-decorticator above referred to. From these pre-decorticating rollers the fiber with its broken shives or shells will be delivered to a drier of any suitable means such, for example, as the endless feed belt 17 that runs over power driven rollers 18 mounted on an extension of the frame 10 and driven in the direction of the arrows marked on Fig. 2.

The drier includes a long drying oven formed by an extended casing or housing 19 shown as mounted on the frame section 10a. The casing 19 is open at its ends to receive and discharge the fiber that is to be dried therein. The fiber is carried through the drier by a very long endless carrier belt 20 preferably of the open or screen type. This belt 20 runs over guiding and driving pulleys 21 and 22 journaled on the frame 10a.

Within the lower part of the casing 19 is a plurality of fans or blowers 23 that have air intake ports 24 and are raised to discharge blasts of air upward through the belt 20 and the fiber carried thereby. By the action of these fans or blowers, the fiber, the shives of which have already been broken up, will be more completely dried and the remaining shives rendered more brittle and hence easier to remove by the breaking rollers of the final or secondary decorticator. In the actual machine the casing 19 will be very long and there would be a much larger number of said fans or blowers than illustrated in the drawings.

From the drier the dried straw will be delivered to a so-called spreader belt by suitable means such as the endless feed belt 25 that runs over

suitable supporting rollers 26 and is driven in the direction of the arrows marked on Fig. 2a. This tooth equipped spreader belt 27 runs over power driven sprockets 28 suitably mounted on the frame section 10b. Belt 27 is driven in the direction of the arrows marked on Fig. 2a. The straw or fiber y, in the arrangement illustrated, is carried under floating presser rollers 29 and between lower and upper corrugated power driven feed rollers 30 and 31, which last noted feature however constitutes no important part of the present invention.

The spreader belt 27 delivers the fiber in an evenly spread out condition to the final or secondary decorticator. This last noted decorticator involves power driven lower and upper corrugated breaking rollers 32 and 33 that are journaled in suitable bearings on the frame section 10c and are power driven in the direction of the arrows marked on Fig. 2a. The upper rollers 33 may be and preferably are yieldingly mounted by means such as that disclosed in the Wessel Patent No. 1,592,317 above identified.

By the action of the corrugated breaking rollers of this final or main decorticator the thoroughly dried and brittle shives or shells remaining on the fiber will be broken up and much thereof will be dropped from the machine on the passage of the fiber between the cooperating corrugated breaking rollers.

The breaking of the fiber will be greatly facilitated by providing the rollers of the decorticator with corrugations that increase in number and fineness in the rollers from the left toward the right in respect to the drawings, which is in the direction of the movement of the fiber.

The last of the breaking rollers 32 and 33 deliver to first of a series of concaves 34 that are connected at 35, see particularly Figs. 1b and 2b. Some, or if desired all, of the concaves 34 will be perforated so that certain of the shives and seeds, if any, will pass therethrough. At the junction 35 of the concaves toothed grate sections 36 are applied. Large tooth equipped drums or cylinders 37 work immediately over the concaves 34 and cooperate therewith to produce a scutching or stripping action and further remove the broken shives from the fiber. These so-called scutching drums are carried by shafts 38 journaled in suitable bearings on the frame section 10c and driven in the direction of the arrows marked on Fig. 2b. The drums 37 are covered by hoods 39. There is a tendency for the toothed drums to carry upward and over part of the fiber, and to prevent this fans or blowers are applied at the junction of the hoods 39 and are applied to produce downward air blasts to prevent the said carrying over action and to force the light materials from the one drum to the next following drum. These fans or blowers involve casings 40 that are open at 41 for the downward discharge of the air blast as stated.

Working in each fan casing 40 is a blade equipped fan head 42 that is driven in the counterclockwise direction in respect to Figs. 1b and 2b. The last concave 34 leads to a discharge spout 43 that delivers to toothed picker drum or roller 44 that works over a fixed concave 45. The picker drum 44 is carried by a shaft 46 journaled in suitable bearings on the frame 10c and driven in a counterclockwise direction in respect to Figs. 1b and 2b.

The picker drum 44 acts to comb out and straighten the fiber and deliver the same to the first pair of a multiplicity of corrugated finish-

ing rollers 47 and 48 that are journaled in suitable bearings directly or indirectly on the frame section 10c and are driven in the direction of the arrows marked on Fig. 2b so as to progressively feed the fiber from the left toward the right in respect to said views. The corrugations of the rollers 47 and 48 are preferably finer than those of the rollers 32 and 33 and serve to break and loosen from the fiber the finer shives or woody portions adhering to the fiber.

The last pair of breaking rollers 47 and 48 delivers to final toothed scutching or picking drum 49 that works over a concave 50 that is similar to one of the concaves 34. This drum 49 is carried by a shaft 51 journaled in suitable bearings on the frame section 10c and driven in a counterclockwise direction or in the direction of the arrows marked on Fig. 2c. A fan casing 52 having a downwardly opening air discharge passage 53 is applied over the top of the delivery side of the drum 49. Working in the fan casing 52 is a fan head 54 that is driven in a counterclockwise direction in respect to Fig. 2c and serves to blow the fiber downward on to an endless carrier belt 55 that works over driven rollers 56. A conveyer belt 55 delivers the fiber between a plurality of cooperating corrugated final breaking rollers 57 journaled in suitable bearings on the frame section 10d and arranged to deliver the fiber to the large breaker drum 58 carried by a shaft 59 journaled on the frame 10d and driven in a counterclockwise direction in respect to Fig. 2c.

The drum 58 carries the fiber under a plurality of presser rollers 60. The rollers 58 and 60 will usually be slightly roughened or slightly corrugated but may be substantially smooth. The drum 58 will be power driven in the direction indicated but the rollers 60 may be frictionally driven. The said drum and cooperating rollers constitute a machine sometimes designated as a breaker, the function of which is to smooth down the fiber.

The fiber delivered from the said breaker will be in condition for spinning or for final treatment for spinning. When the fiber is to be baled, it will be delivered to a baling machine of any suitable or commercial form indicated in Figs. 1c and 2c as an entirety by the numeral 61. In said views 1c and 2c the breaker delivers to a casing 62 that has a delivery spout 63 arranged to discharge the fiber from the breaker to the baling machine; and in this arrangement a blade or tooth equipped picker drum 64 is arranged to work in the receiving end of the spout 63 and to produce a blowing action that will discharge the fiber through the spout 63.

Insofar as this invention is concerned, the various rotary parts of the machine may be driven by any suitable means. In fact, the various drums and rollers might be individually driven by electric motors or the like or by various gears and belts.

In the drawings conventional gear and belt drive are suggestively indicated diagrammatically, but as these drives constitute per se no part of the present invention, the elements thereof are not specifically described or marked with identifying characters. The only thing important about the drive mechanism is that the several rotary drums and rollers and rotary parts are driven in the direction of the arrows on the drawings or as otherwise herein above stated.

Summary of operation

The operation of the complete machine designed as illustrated in the drawings has already been generally indicated but may be briefly summarized as follows: The fiber, assumed to be ramie, will first be acted upon by the rollers of the pre-decorticator or primary breaking rollers and the shives or woody particles of the fiber will be broken and some thereof removed and dropped from the machine. The shives or woody portion of the fiber is thus broken to an extent that the drying process may be readily carried out and the gummy portions of the fiber at least in part removed.

Next the fiber thus treated is carried through the drier by the long feed belt 20. This drier in actual practice would be very long, in some machines as much as fifty feet or more, and, of course, the fans or blowers will be in greater number than shown in the drawings. In the movement of the fiber through this drier the remaining shives will be dried and made brittle and hence more readily removable.

From the drier the fiber will be delivered to the spreader belt 21 and by the latter carried to the final predecorticator which includes the second group of corrugated breaking rollers, and by the action of the latter breaking rollers the brittle shives or woody particles will be much more completely broken up and removed from the fiber, and the removed shives will be dropped from the machine.

The fiber delivered from the breaking rollers of the second or main pre-decorticator will be delivered to the first of the series of scutching or stripping drums 37 and by the successive drums the fiber will be removed from the fiber and the fiber more or less combed out. The fans or blowers 40-42 in the operation as already described perform the important function of effecting proper delivery of the fiber from the one toothed drum 37 to the other and from the last toothed drum to the picking drum 44, from which latter the fiber will be delivered between the finely corrugated final breaking rollers 47-48. The fiber delivered from the last of the rollers 47-48 will be nearly or quite free from the shives or woody particles.

What is claimed is:

1. In a machine of the kind described, a pre-decorticator involving cooperating breaking rollers, a drying apparatus receiving from said pre-decorticator, a secondary decorticator involving breaking rollers receiving from said drier, and a toothed scutching drum and cooperating concave receiving from the last rollers of said secondary decorticator, in further combination with an additional or third set of cooperating breaking rollers receiving from said scutching drum.

2. In a machine of the kind described, a pre-decorticator involving cooperating breaking rollers, a drying apparatus receiving from said pre-decorticator, a secondary decorticator involving breaking rollers receiving from said drier, and a toothed scutching drum and cooperating concave receiving from the last rollers of said secondary decorticator, in further combination with an additional or third set of cooperating breaking rollers receiving from said scutching drum, and a further and additional toothed scutching drum receiving from said third set of breaking rollers.

3. In a machine of the kind described, a pre-decorticator involving cooperating breaking rollers, a drying apparatus receiving from said pre-

ers, a drying apparatus receiving from said pre-decorticator, a secondary decorticator involving breaking rollers receiving from said drier, and a toothed scutching drum and cooperating concave receiving from the last rollers of said secondary decorticator, in further combination with an additional or third set of cooperating breaking rollers receiving from said scutching drum, and a further and additional toothed scutching drum receiving from said third set of breaking rollers, 10 a breaking drum and cooperating rollers receiving from said third set of breaking rollers.

4. In a machine of the kind described, a pre-decorticator involving cooperating breaking rollers, a drying apparatus receiving from said pre-decorticator, a secondary decorticator involving breaking rollers receiving from said drier, and a toothed scutching drum and cooperating concave receiving from the last rollers of said secondary decorticator, in further combination with an additional or third set of cooperating breaking rollers receiving from said scutching drum, and a further and additional toothed scutching drum receiving from said third set of breaking rollers, 20 a breaking drum and cooperating rollers receiving from said third set of breaking rollers, and a picking drum and concave receiving from said breaking drum.

5. In a machine of the kind described, a pre-decorticator involving cooperating breaking rollers, a drying apparatus receiving from said pre-decorticator, a secondary decorticator involving breaking rollers receiving from said drier, and a toothed scutching drum and cooperating concave receiving from the last rollers of said secondary decorticator, in further combination with an additional or third set of cooperating breaking rollers receiving from said scutching drum, and a further and additional toothed scutching drum receiving from said third set of breaking rollers, 30 a breaking drum and cooperating rollers receiving from said third set of breaking rollers, and a picking drum and concave receiving from said breaking drum.

6. In a machine of the kind described, a pre-decorticator involving cooperating breaking rollers, a drying apparatus receiving from said pre-decorticator, a secondary decorticator involving breaking rollers receiving from said drier, and a toothed scutching drum and cooperating concave receiving from the last rollers of said secondary decorticator, and in which structure there is a plurality of said cooperating scutching drums and concaves, the said concaves being joined between 40 said scutching drums, and in further combination with blowers arranged to produce a downward blast of air between said scutching drums and over the point of junction between said concaves.

7. In a machine of the kind described, a pre-decorticator involving cooperating breaking rollers, a drying apparatus receiving from said pre-decorticator, a secondary decorticator involving breaking rollers receiving from said drier, and a toothed scutching drum and cooperating concave receiving from the last rollers of said secondary decorticator, and in which there is a plurality of said cooperating scutching drums and concaves, the said concaves being joined between 50 said scutching drums, a third set of cooperating 55 breaking rollers receiving from the last of said scutching drums and concaves.

8. In a machine of the kind described, a pre-decorticator involving cooperating breaking rollers, a drying apparatus receiving from said pre-

decorticating, a secondary decorticating involving breaking rollers receiving from said drier, and a toothed scutching drum and cooperating concave receiving from the last rollers of said secondary decorticating, and in which there is a plurality of said cooperating scutching drums and concaves, the said concaves being joined between said scutching drums, a third set of cooperating break-

ing rollers receiving from the last of said scutching drums and concaves, blowers applied to blow a blast of air downward against the upwardly moving delivery sides of said tooth drums.

5
LELAND O. WALKER.
Administrator of the Estate of Karl Wessel, Deceased.
